TRAFFIC CONTROL SYSTEM

John L. Biach and Harry A. Wilcox, New Haven,
Conn., assignors to The Engineering and Re-
search Corporation, East Norwalk, Conn., a
corporation of Connecticut

Application April 23, 1930, Serial No. 446,480

30 Claims. (Cl. 177—337)

This invention relates to a traffic system capable of use in numerous different associations but primarily intended for employment with vehicle lanes such as roadways, and particularly at points of intersection of roadways, the present invention aiming to provide an automatic system by means of which traffic will be expeditiously handled and which system to the greatest extent if not completely will be controlled in its 10 functioning by the presence of traffic along the vehicle lanes.

Subject matter relating to the "periodic call" feature disclosed in the present application is claimed in application Serial No. 73,156 filed April 7, 1936, by Charles D. Geer as a division of 15 the present application. Such subject matter is not claimed in the present application.

Subject matter relating to the "speed proportional control" feature disclosed in the present 20 application is claimed in application Serial No. 446,479 filed April 23, 1930, by Frederick G. Kelly, Jr., and no claims are made in the present application to such subject matter.

It is an object of the invention to provide an 25 arrangement of apparatus furnishing a system of this character and by means of which traffic will be handled with maximum expediency and minimum delay periods and in which moreover the system will embrace a factor of safety such 30 that the danger of accidents between vehicles or between vehicles and pedestrians will be reduced to a minimum, if not entirely eliminated.

A further object is that of providing a system 35 of this character, the several units of which will be individually simple and rugged in construction and embrace relatively few parts, these units when assembled providing a system operating over long periods of time with freedom from mechanical and/or electrical difficulties. Moreover, these units to the greatest extent will be 40 capable of individual adjustment so that while at the time of their manufacture, conditions may generally be approximated, adjustments may be made at the time of or subsequent to their installation at an actual traffic intersection so as to 45 take into account the characteristics individual to the traffic flow along the vehicle lanes comprising such intersection.

A still further object is that of providing a traffic 50 control system in which in the functioning of the systems, account may be taken of the amount of waiting traffic as well as the amount of moving traffic, so that on the one hand undue delays will not be incurred and on the other hand, the danger of a relatively slow moving

vehicle becoming trapped at the intersection will be reduced to a minimum.

Still another object is that of construction of a system, the several units of which will function in the event of one condition of traffic to substantially instantaneously transfer the right of way from one vehicle lane to the intersecting vehicle lane upon the approach of a vehicle along the latter, but in the event of vehicles passing along the first vehicle lane and approaching the 10 intersection will delay this transfer of right of way for a period adequate to assure safety of transfer.

With these and further objects in mind, reference is had to the attached sheets of drawings 15 illustrating one practical embodiment of the invention and in which:

Figure 1 is a diagrammatic view showing a highway intersection employing a signal system embodying our invention;

Fig. 2 is a detailed view showing a section of a vehicle actuated control device;

Figs. 3 and 4 show diagrammatic representations of timing mechanisms;

Figs. 5 and 6 together comprise diagrammatic 25 views showing the circuits of an apparatus for operating the signal at intersecting traffic lanes.

Fig. 7 shows an enlarged and more detailed view of the ratcheting mechanism employing the rack 185' in Fig. 5 for example.

A self regulating automatic traffic control system embodying our invention may comprise three parts: a vehicle actuated control, traffic responsive device or detector placed in or at the side of a road or vehicle lane, an electrical time limiting control system, and a signal device to indicate right of way to traffic. A function of the vehicle actuated control device is such that vehicles approaching on the several traffic lanes actuate various electrical control circuits. These actuations control the operation of the electrical time limitation control system, which in turn controls the right of way device. The right of way device, to inform the traffic in each street when to go and when to stop, may be the standard red, yellow and green lights now in general use, but may also be any other convenient or desirable form. The vehicle actuated control may be of several types as hereinafter mentioned:

One means actuated by the approaching vehicle may be of a mechanical nature such as a mechanical switch located in or at the side of the street, an electrical contact being made upon passage of the vehicle.

Another means for detecting and recording the presence of an approaching vehicle may be a beam of light projected across the highway and received upon a photo-electric or light sensitive electrical cell, so that an approaching vehicle causes an interruption or fluctuation in an electrical current passing through the photo-electric or light sensitive cell.

An electrical magnetic device located in the street or at the side of the street may also be arranged in such a manner that an approaching vehicle shall actuate the device to control an electric circuit.

Obviously, any other form of vehicle indicator could be used.

The time limit control circuit operates as follows:

Assume that there are no vehicles approaching on the intersecting streets, designated for example, by A and B. Then the right of way will be indicated to the street which last required it; for example, A Street. A vehicle approaching from B Street now operates the B Street actuating means, and the control mechanism, after showing a suitable warning signal, transfers right of way to B Street. B Street now has the right of way and vehicles approaching on it may cross the intersection. The right of way will be transferred back to A Street under any one of the following conditions:

Condition I.—If a vehicle approaches on A Street and all B Street traffic has passed the intersection.

Condition II.—If a vehicle approaches on A Street and B Street traffic is still moving at the end of a predetermined period (such as 30 seconds), the right of way is transferred to A Street.

Condition III.—If no vehicles approach on A Street, then, whether or not traffic is moving on B Street, right of way will be called to A Street and will be yielded to A Street as under Conditions I and II above.

The various periods are controlled by suitable timing mechanisms.

Provision to transfer the right of way to A Street as outlined under Condition I above is accomplished through the use of a timing mechanism which provides sufficient time for the individual B Street vehicles to cross the intersection. This timing mechanism is reset toward its starting position each time a vehicle operates the B Street actuating means. Hence, if no further vehicles approach on B Street, this timing mechanism will eventually complete timing the period it is set for; and when such time is reached, the right of way is transferred to A Street. The action is of course similar when the right of way is transferred from A Street to B Street.

To provide for Condition II mentioned above, in which continuous B Street traffic must be interrupted, another timing mechanism is provided which is not reset by vehicles on B Street, and which starts timing when the vehicle approached on A Street. When it has timed the period it is set for, the right of way is transferred to A Street.

To provide for Condition III mentioned above, we provide another timing mechanism which starts timing B Street right of way as soon as right of way appears on B Street. When it has timed the period it is set for, it calls the right of way to A Street, similar to the way in which right of way would be called to A Street by a vehicle approaching on A Street and thus simulates the effect of actuation of the vehicle actu-

ated control on A Street by such a vehicle. After right of way has been called in this manner, it will be transferred as outlined in either Condition I or Condition II, depending upon conditions in B Street.

When right of way is transferred as in Condition II, vehicles are on B Street which have not had sufficient time to cross the intersection, even though they have actuated the B Street actuating means. The control system is left in such a condition that as soon as A Street traffic permits, right of way will be transferred to B Street without requiring any additional actuation of the B Street vehicle actuated means.

The timing mechanism which is reset by traffic, is so arranged that it may be reset in accord with the speed of the vehicle causing the resetting. And thus the time or protection period given each vehicle is commensurate with the speed of the vehicle. In this manner, no vehicle receives an unnecessarily long protection period; thus avoiding needless delay in the interfering lane.

The chief function of the warning signal when a stop signal is changing to right of way, is to indicate to waiting vehicles that such change is about to occur, and to get ready to proceed. But, when the change is from right of way to stop, it indicates to moving vehicles that they are about to lose right of way, and accordingly the vehicles must be brought to a stop. The warning signal thus acts as a very important safeguard.

Whenever right of way is transferred as outlined in Condition I, all traffic has ceased on the lane which is losing right of way. Thus, there are no vehicles about to lose right of way, and consequently the warning signal may be quite short. But when right of way is transferred, as outlined in Condition II, some vehicles are about to lose right of way, and accordingly a longer warning signal should be given. This is accomplished by providing a mechanism which times the warning signal in a different way, depending whether the right of way is transferred as outlined in Condition I, or whether it is transferred as outlined in Condition II.

If several vehicles have passed the actuating means while being given the stop signal, some time will elapse, after they have been given the right of way signal, before the last of said vehicles gets into motion. This time may be quite considerable, and may exceed the protection period provided by the resettable timing mechanism. We thus provide an additional timing mechanism, the time period of which is proportional to the number of vehicles that have passed the actuating means, but are not allowed to proceed. This timing mechanism begins to time as soon as right of way appears on its street; and only after it has finished timing its period, may the resettable timer begin to operate.

While there has been described above a self regulating automatic traffic control system embodying this invention, and there has been shown that this invention may comprise three interconnected parts, there will now be described in detail the construction of one complete and specific system embodying the invention:

Referring to Fig. 1 of the drawings, there is shown a complete self regulating automatic traffic control system applied to intersecting streets A and B. The vehicle actuated controls are indicated by the numbers 1, 2, 3 and 4. The signal means in this particular embodiment is, as pre-

ferred, visual, and is indicated at 5. It embraces red and green electric lamp reflectors or lenses visible from either direction on A Street, but not visible on B Street; red and green electric lamp reflectors, or lenses, visible from either direction on B Street, but not visible on A Street; and preferably a yellow electric lamp lens or reflector visible from both streets. The electrical time limiting control is indicated by 6. The unshaded lines indicate controlling circuits. Thus, the vehicle actuated devices in A Street control the electrical time limiting control 6, and so do the vehicle actuated devices in B Street. The time limiting control 6 controls the signal 5.

Fig. 2 shows one form of vehicle actuated device consisting of a ramp 7 hinged at 8 and forced into an elevated position by spring 9. The top surface of the ramp may be substantially at the level of the street. When the wheel of a vehicle passes over the ramp, the weight of the vehicle depresses ramp 7, causing contacts 10 and 11 to be pressed together, closing circuit between wires 12 and 13. When the wheel leaves ramp 7, spring 9 forces the ramp 7 into an elevated position, breaking circuit between wires 12 and 13 by separating contacts 10 and 11. The vehicle actuated devices in A Street are connected in parallel. The vehicle actuated devices in B Street are also connected in parallel.

The time limiting control uses several timing mechanisms. One embodiment of such a timing mechanism is shown in Fig. 3. When a source of voltage supply is connected between wires 14 and 15, current flows from wire 14 through wire 16, relay 17, and wire 18, to wire 15, operating relay 17. This allows current to flow from wire 14 through adjustable resistance 19, contact 20, armature 21, wire 22, wire 23, condenser 24, wire 25, to wire 15. Thus the voltage of the supply is applied to condenser 24 through resistance 19, and the voltage of the condenser begins to build up at a definite rate determined by the size of the condenser, the resistance 19, and the voltage of the supply. Shunting condenser 24 is a circuit including a glow tube 26, and a relay 27. The glow tube comprises a bulb containing a suitable gas into which electrodes 28 extend. This tube has such a characteristic that it is normally non-conducting, but when the voltage across its terminals reaches a certain critical or threshold value, the gas ionizes and becomes a good electrical conductor and will not become non-conducting again until the voltage across its terminals has dropped considerably below the critical ionizing voltage. The voltage of the supply is greater than the critical voltage of the tube. When the voltage across the condenser is built up to the critical voltage of the tube, the tube suddenly becomes conducting, causing current to flow momentarily from condenser 24 through tube 26, and relay 27, causing relay 27 to operate. This would effect only a momentary closure of the relay were it not for the locking circuit comprising contact 29, armature 30, and wire 31, which is established when relay 27 operates. This places relay 27 directly across the supply, and relay 27 remains energized.

The interval elapsing between the application of the supply voltage to wires 14 and 15, and the operating of relay 27, is the period timed by the mechanism. By suitable adjustment of resistance 19, any desired interval may be obtained. When relay 27 operates it may be used to actuate one or more armatures such as 30 in addition to

armature 30. These additional armatures will be used as described below.

Relay 27 remains energized as long as the supply voltage is connected between wires 14 and 15. If the supply voltage is disconnected, the energizing circuits of both relay 17 and relay 27 are interrupted, both relays become deenergized and drop to their deenergized positions. When relay 17 becomes deenergized, it causes armature 21 to touch contact 32. This shunts adjustable resistance 33 across the terminals of condenser 24, and any energy that may be stored in condenser 24 is dissipated in resistance 33. The rate of dissipation of energy may be varied at will by proper adjustment of resistance 33.

Wires 14 and 15 may be called conveniently the energizing wires of the timing mechanism and are accordingly marked E—E.

Figs. 5 and 6 combined show a wiring diagram of a traffic control system embodying the invention. This wiring diagram is arranged symmetrically with respect to an imaginary vertical line through the two figures with the apparatus associated with A Street on the left and that associated with B Street on the right side of these figures. The ratcheting mechanisms and associated relays and timer for the "variable increment" feature for the respective streets are shown schematically in Fig. 6.

In the wiring diagram with the various switches, in the positions indicated, the system is so arranged that right of way remains showing on the street which last had right of way, in the event that there be no traffic on either street. Assuming that A Street last had right of way, instantaneous operating relay 34 will be energized, thus lighting the A Street green light and B Street red light through wire 35, wire 36, contact 37, armature 38, and wire 39. It will also be noted that timing mechanisms 40 and 41 are energized, and also instantaneous operating relay 42. The action of the apparatus under various traffic circumstances will now be described.

CASE I.—Single vehicle approaching on B Street.—Assume a vehicle approaches on B Street actuating one of the vehicle actuated devices located there, closing circuit between wires 12 and 13. The B Street vehicle actuated control devices are connected to wires 43 and 44; thus whenever one of the B Street vehicle actuated devices is actuated, the actuating circuit of relay 45 is closed and it operates. This momentarily closes the energizing circuit of relay 46 through wire 47, wire 48, wire 49, contact 50, armature 51 and wire 52. Relay 46 causes armature 52 to touch contact 53, locking in relay 46 through wire 54, contact 55, armature 56, wire 57 and wire 62. This locking circuit is necessary because relay 45 operates only momentarily, and were it not for this locking circuit, relay 46 would also operate only momentarily. The operating of relay 46 interrupts the energizing circuit of timing mechanism 40, which had been made through wire 47, armature 53, contact 54, wire 55, contact 56, armature 57, wire 58, wire 59, contact 60, armature 61, and wire 62. Timing mechanism 40, its energizing circuit being broken, allows its relay 27 to drop to its de-energized position, releasing armature 63. The energizing circuit of relay 34 which had been made through wire 64, armature 63, contact 65, wire 66, switch 145, wire 67, switch 145, contact 68, armature 69, wire 70, contact 71, armature 72 and wire 73, is now broken by the deenergized position. Armature 38 separating from contact 37 extinguishes

the A Street green light and B Street red light. At the same time, the yellow light is energized through wire 39, armature 38, contact 74, wire 75, wire 76, contact 77, armature 78, and wire 79. At the same time, timing mechanism 80 is energized through wire 81, armature 82, contact 83, wire 84, wire 85, armature 86, contact 87, wire 88, contact 89, armature 90, wires 91 and 62. Timing mechanism 80 is similar to the timing mechanism shown in Fig. 4, and similarly, E—E represent the energizing wires. Assume that the resistance 19 in this timing mechanism is adjusted so that the mechanism times an interval of 3 seconds. When relay 34 was de-energized, it de-energized relay 42 because the energizing circuit of relay 42, consisting of wire 73, armature 96, contact 97, wire 98, wire 99, contact 100, armature 82, and wire 81, is broken when armature 82 separates from contact 100. After timing mechanism 80 has been operating for 3 seconds, its condenser discharges through its tube in the manner described above, and its relay, corresponding to relay 27 operates, causing armature 101 to separate from contact 102, and to touch contact 103. When armature 101 leaves contact 102, it breaks the operating circuit of timing mechanism 41 and timing mechanism 41 becomes de-energized. The energizing circuit of timing mechanism 41 consisted of wire 104, armature 101, contact 102, wire 105, switch 106, wire 107, contact 108, armature 109, and wire 110. When armature 101 touches contact 103, relay 111 is energized through wire 104, armature 101, contact 103, switch 146, wire 112, wire 113, switch 146, contact 114, armature 115, wire 116, contact 117, armature 53 and wire 47. Relay 111 operates armature 78. Armature 78 separates from contact 77 extinguishing the yellow light and touches contact 118, lighting the B Street green light and A Street red light through wire 78, armature 10, contact 118, wire 119 and wire 120. The right of way is now being given to B Street and the vehicle which approached there may cross the intersection. Timing mechanism 121 is the mechanism which provides the necessary time for the individual vehicles on B Street to cross the intersection. This timing mechanism is also similar to the mechanism shown in Fig. 3, E—E representing the energizing wires. Assume that the resistance corresponding to resistance 19 is adjusted so that timing mechanism 121 times a period of 10 seconds. The energizing circuit of timing mechanism 121 is made through wire 52, armature 51, contact 122, wire 123, switch 124, wire 125, contact 126, armature 63 and wire 64. It will thus be noticed that this circuit is completed when timing mechanism 40 becomes de-energized.

CASE II.—Single vehicle approaching on A Street immediately after transfer of right of way to B Street.—The action of the apparatus is similar to the action as described under Case I, up to the time right of way is actually transferred to B Street. The single vehicle now approaching on A Street operates, for example, ramp 2. The ramps in A Street are connected across wires 127 and 128, and thus the vehicle on A Street causes a momentary operation of relay 129. This causes relay 42 to operate by energizing it through wire 110, armature 109, contact 130, wire 131, and wire 73. Relay 42 locks itself in through armature 96, contact 97, wire 88, contact 132, armature 133, wire 134 and wire 81. Contact between armature 133 and contact 132 is made because when relay 129 operated, it separated

armature 109 from contact 108, thus breaking the energizing circuit of timing mechanism 41, which immediately dropped to its de-energized position. Assuming that only a single vehicle was approaching on B Street, then, after 10 seconds, timing mechanism 121 will operate and armature 90 will separate from contact 95 and 89. In separating from contact 89, armature 90 breaks the energizing circuit of timing mechanism 80 which becomes de-energized, causing armature 101 to leave contact 103. This de-energizes relay 111, which allows armature 78 to separate from contact 118, extinguishing the B Street green light and A Street red light. At the same time armature 78 touches contact 77, lighting the yellow light as described above. In de-energizing, relay 111 allows armature 61 to touch contact 60, which re-establishes the energizing circuit of timing mechanism 40. Timing mechanism 40 is similar to the mechanism shown in Fig. 4; and we shall assume that its resistance, corresponding to resistance 19, is so adjusted that the mechanism times a period of 3 seconds. After being energized for 3 seconds, timing mechanism 40 operates, separating armature 63 from contact 126, and allowing armature 63 to touch contact 65. In separating from contact 126, armature 63 breaks the operating circuit of timing mechanism 121, which becomes de-energized. At the same time, armature 63, in touching contact 65 energizes relay 34. Relay 34 operates armature 38, which leaves contact 74, extinguishing the yellow light, and touches contact 27, lighting the A Street green light and B Street red light, and the right of way is again being given to A Street and the vehicle which approached there may cross the intersection.

The above two cases describe transfer of right of way from one street to another in response to a vehicle approaching on this street where right of way is not being given. It will be noticed that once a vehicle has been given right of way, it will retain right of way for a certain minimum period, for example, 10 seconds; and even though a vehicle approached on the other street, right of way cannot be taken away until the end of this minimum period which we assume is sufficient time for the vehicle to cross the intersection. If all traffic has ceased, then the timing mechanism which provides this minimum period, (for street A this would be timing mechanism 40), is in its operated condition, and should a vehicle approach on the other street, right of way will be transferred immediately. If traffic has not ceased, the above mentioned timing mechanism will not be in its operated condition, and should a vehicle approach on the other street, it must wait until this timing mechanism has operated.

CASE III.—Single vehicle approaching on B Street followed within ten seconds by a second vehicle on B Street.—Assuming the right of way is being shown to A Street and there is no traffic on A Street, then the first vehicle approaching on B Street will transfer right of way to B Street as described in Case I. If a second vehicle approaches on B Street, actuating either ramp 1 or 3, this will cause relay 45 to operate momentarily breaking circuit between armature 51 and contact 122. This will break the energizing circuit of timing mechanism 121. We have assumed that timing mechanism 121 times a period of 10 seconds. Assuming the second vehicle to have approached within 10 seconds from the time the first vehicle approached, condenser 24 of this

timing mechanism will not be charged up to the critical voltage of tube 26, and relay 27 will not have operated. The breaking of the energizing circuit de-energizes relay 17 and the charge which has accumulated on the condenser will be dissipated in resistance 33, as described previously. Relay 45 is of course energized only for a short time, and consequently the energizing circuit of timing mechanism 121 is immediately re-established. But it will be noticed that condenser 24 has been de-energized, and consequently a full 10 seconds must elapse before the condenser will again be charged to the critical voltage of tube 26. The operation of the system under Case II has shown that right of way cannot be taken away from B Street once it has received it, until timing mechanism 121 has operated. Thus, whether or not, in the meantime, a vehicle has approached on A Street, the second vehicle that approached on B Street receives a full 10 seconds in which to cross the intersection. It is apparent that this operation will be repeated if additional vehicles approach on B Street. As soon as vehicles cease approaching on B Street, timing mechanism 121 will, after 10 seconds have elapsed since the last actuation of either ramp 1 or 3, operate, and assuming a vehicle to have approached on A Street, the right of way will be transferred to A Street, as described under Case II. Once right of way has been transferred to A Street, the operation of the system, should more vehicles approach on A Street, is precisely as described above. Relay 129 performs the same function for A Street that relay 45 performs for B Street; and, similarly, timing mechanism 41 operates when right of way is being given to A Street, just as timing mechanism 121 operates when right of way is being given to B Street.

In describing Case III, it was assumed that after right of way was transferred to B Street, a vehicle approached on A Street. If no vehicles approach on A Street, then after the last car has passed B Street, timing mechanism 121 will operate and right of way will simply remain on B Street. This is because, even though the energizing circuit of timing mechanism 80 is interrupted when armature 90 separates from contact 89, timing mechanism 80 remains energized because power continues to be applied through wire 135, contact 136, armature 72, and wire 73. This is because, since no vehicle has approached on A Street, relay 42 is de-energized. If vehicles should again come on B Street, timing mechanism 121 will again be de-energized, as described above. The B Street traffic will again be protected and it cannot lose right of way until all of it has passed the intersection. It is apparent that as long as no vehicles approach on A Street, B Street traffic can retain right of way indefinitely.

CASE IV.—Continuous traffic on B Street with a vehicle waiting on A Street.—When this condition occurs, timing mechanism 121 will be continually de-energized or re-set by the B Street vehicles, and right of way would remain indefinitely on B Street. This is permissible if there is no traffic on A Street. But should vehicles approach on A Street, there must be some limitation to the length of time B Street can continue to hold right of way after vehicles have approached on A Street. This is accomplished with timing mechanism 137. This timing mechanism is again similar to the type shown in Fig. 3, and we shall assume that its resistance 19 is

so adjusted that the mechanism times a period of 30 seconds. This timing mechanism does not begin to operate until a vehicle approaches on A Street. When this happens, relay 42 becomes energized and current flows from wire 73, through armature 72, contact 71, wire 138, the energizing wires E—E of timing mechanism 137, wire 125, contact 126, armature 63, and wire 64. It will furthermore be noticed that this timing mechanism is not re-set by vehicles on B Street, and once energized, uninterruptedly continues to time until the end of its timing period, for example, 30 seconds. Assuming B Street traffic to be continuous, then after 30 seconds, timing mechanism 137 will operate armature 86, separating it from contact 81. This de-energizes timing mechanism 80 which in turn de-energizes relay 111, and right of way is transferred to A Street as described above under Case II. The difference is that relay 46 remains energized because its locking circuit continues to be made through contact 95 and armature 90, since timing mechanism 121 has not been energized long enough to operate. Thus, after right of way is transferred to A Street, relay 46 is energized, which is equivalent to the approach of a vehicle on B Street. The system thus provides that without requiring an additional actuation of either vehicle actuated control 1 or 3, right of way will return to B Street as soon as traffic on A Street permits. This procedure is necessary because a vehicle may approach on B Street within a second or two from the time right of way is going to be taken from B Street, and not having had sufficient time to cross the intersection, these B Street vehicles would be stranded. The system is thus arranged so that when right of way is transferred, due to the operation of timing mechanism 121, relay 46, during such a transfer, becomes de-energized. But, should timing mechanism 137 transfer right of way, relay 46 will not become de-energized, the right of way will thus be recalled to B Street, so that vehicles on B Street which did not receive a full 10 seconds in which to cross the intersection, will be given ample time to do so. Timing mechanism 138 performs the same function for A Street that timing mechanism 137 performs for B Street. The energizing circuit of timing mechanism 139 consists of wire 47, armature 53, contact 117, wire 140, energizing wires E—E, wire 105, contact 102, armature 101, and wire 104.

We have thus provided a very flexible traffic control system. It is arranged that once right of way is given to a particular street, in response to vehicles approaching there, each vehicle receives a certain protection period from the time it actuates the ramp in the street, during which it may cross the intersection, and is protected against opposing traffic. If a vehicle approaches on the street where the stop sign is being given, right of way will be transferred to it immediately if traffic has ceased on the intersecting street. If traffic has not ceased, this vehicle must wait until the last vehicle on the intersecting street has had a full minimum period in which to cross the intersection. However, vehicles do not have to wait indefinitely should there be continuous traffic on the opposing street. The system provides that the vehicle need not wait more than a certain predetermined time. At the end of this time, the continuous traffic on the opposing street is interrupted to allow the waiting vehicle or vehicles to cross the intersection. The system, however, is left in such a condition that

without requiring the approach of further vehicles, the right of way will eventually revert to the street where continuous traffic was interrupted, to allow the vehicles which did not have sufficient time to cross the intersection to do so.

In describing the operation of the embodiment of the timing mechanism shown in Fig. 3, it was stated that the rate of discharge or re-set could be varied at will by proper adjustment of resistance 33. This resetting occurs whenever the energizing circuit E-E is interrupted. While the rate of discharge may be determined by resistance 33, the actual amount of discharge depends upon the length of time the energizing circuit is interrupted. If this time is long, practically all of the stored energy will be dissipated in resistance 33. Thus when the energizing circuit is re-established, charging of condenser 24 will start with practically no stored energy in the condenser, and the time required to charge the condenser will be the time necessary to charge it from zero voltage to the critical voltage of tube 26. If the time of re-set is short, condenser 24 will not be completely re-set, and thus when the energizing circuit is re-established, charging of condenser 24 will start with a residual voltage on the condenser, and the period timed by the mechanism will be the period necessary to charge condenser from that voltage to the critical voltage of tube 26. The timed period will be shorter by the amount of time that would have been necessary to charge condenser 24 from zero voltage to the residual voltage. It is thus apparent that the amount of re-set depends upon the length of time the energizing circuit is interrupted.

The above is the action of the apparatus if the energizing circuit is always interrupted when condenser 24 has been charged to some particular voltage. In practice, as will appear later, the interrupting of the energizing circuit may occur at all sorts of different voltages. Considering the operation of the device more in detail, it will appear that actual amount of discharge, while depending upon the length of time the energizing circuit is interrupted, also depends upon the voltage to which the condenser has been charged when the energizing circuit is interrupted. Thus, for example, a re-setting impulse of a certain length of time, if occurring when the voltage of the condenser is 180 volts, re-sets the condenser to a voltage of 120; a re-setting impulse of the same length of time, if occurring when the condenser voltage is 150 volts, will re-set the condenser to 100 volts. It thus appears that for a particular setting of resistance 33, re-setting impulses of a certain length of time will re-set the voltage of the condenser to a certain fraction of its voltage. This becomes apparent from a consideration of the discharge equation of a condenser. This equation is:

$$E_t = E_0 e^{-\frac{t}{RC}}$$

E₀ is the voltage of the condenser when discharge was started; E_t is the voltage of the condenser after t seconds; e is the constant value 2.7183; R is the value of the resistance 33; and C the capacity of the condenser. C is of course fixed, and R is assumed set at some particular value. Thus it is obvious that for a particular value of t, the condenser will always be discharged to the same portion of the voltage.

Referring now to Fig. 2, it will be noticed that the vehicle actuated device consisting of ramp 1

is so arranged that circuit between wires 12 and 13 is closed during the time the wheel of the vehicle is on ramp 1. Since the length of time the wheel is on the ramp depends upon the speed of the vehicle, circuit between wires 12 and 13 will be closed for a short period of time, if the vehicle is travelling rapidly, and for a long period of time if the vehicle is travelling slowly. Actuation of either ramps 1 and 3 operates relay 45, and since this relay is directly connected to the circuit closed by ramps 1 and 3, relay 45 will be energized only while the wheel of the vehicle is actually on the ramp, and consequently the length of time armature 51 is separated from contact 122 depends entirely upon the speed of the vehicle. The energizing circuit of timing mechanism 121 is made through armature 51 and contact 122, and further, the energizing circuit of timing mechanism 121 is interrupted for a length of time which depends entirely upon the speed of the vehicle causing such interruption. Referring now to the above description of the operation of the timing mechanism, it becomes apparent that timing mechanism 121, although giving the first vehicle a full 10 seconds in which to cross the intersection, gives succeeding vehicles an additional period which is dependent upon their speed, and consequently, succeeding vehicles are given just sufficient time to cross the intersection, instead of receiving a full, unnecessary 10 seconds. The faster the vehicle travels, the less the re-set, and consequently the less is the time given the vehicle. But, the faster a vehicle travels, the less time it needs.

The above would be the action if succeeding vehicles continually approach just before timing mechanism 121 is about to operate and separate armature 90 from contacts 89 and 95. In practice, traffic rarely approaches in just that manner. For example, the second car may approach within a second or two from the time the first car approached. Thus, if there were no re-setting at all, the second car would receive possibly 8 or 9 seconds in which to cross the intersection, which might be ample. But, the apparatus automatically takes care of just such a condition. If the second car approaches, say, after 2 seconds, timing mechanism 121 will have been energized for only 2 seconds and the voltage built up in its condenser will be quite small. Since, as explained above, the re-setting does not reduce the voltage of the condenser by a certain number of volts, but instead reduces the voltage by a certain portion of the voltage built up, the amount of re-set will be very small, and the additional time given the second vehicle, very small.

Timing mechanism 41, constructed similar to timing mechanism 121, performs the same operation for street A.

Connection II.—The operation described above occur when the various switches are in the positions shown in Figs. 5-6. It may be seen from an inspection of these figures that if switch 141 is closed, relay 42 is continuously energized, thereby causing the right of way to return to A Street not later than 30 seconds after having been given to B Street, if B Street traffic is continuous, or as soon as B Street traffic ceases.

Connection III.—It can be readily seen by inspection of Figs. 5-6 that if the switches are as shown, except that switch 142 is closed, the operation is as described under Connection II, except that the conditions described for A Street and B Street are interchanged.

Connection IV.—It can be seen that with

switches 141 and 142 closed, the right of way is granted alternately to each street and is held by each street for any period between 10 and 30 seconds. If no vehicles actuate the ramp in a particular street during a period of 10 seconds, the 10 second timing mechanism functions to yield the right of way 10 seconds after it is granted. If, on the other hand, when said street is given the right of way, vehicles operate either ramp in said street so that the 10 second timing mechanism continually re-set, the 30 second timing mechanism functions to yield the right of way 30 seconds after it is granted.

Connection V.—The circuit is so arranged that if, for any reason, it is desired to disconnect the traffic actuated means, this can be accomplished by throwing switches 143 and 144 to their down positions. Under these conditions, relays 42 and 46 are continuously energized and the energizing circuits of timing mechanisms 41 and 121 are continuously interrupted. The system will then function to give right of way alternately to A Street and B Street for periods of 30 seconds each.

Connection VI.—If it is desired to operate a system by hand, this can be accomplished by using switches 145 and 146. If both switches are open, relays 34 and 111 are de-energized, and the yellow light will be shown to both streets, as described previously. If switch 145 is then thrown to the down position, relay 34 will be energized and the A Street green light and B Street red light will be shown. By again opening switch 145, the yellow light will again be shown to both streets. If, then, switch 146 is thrown to the down position, relay 111 will be energized, thus lighting the B Street green light and A Street red light. By opening switch 146, the yellow light will again be shown to both streets. Thus the lights can be operated manually in any desired manner.

Connection VII.—By closing switch 147, or by applying power to the two wires marked "To fire headquarters," this will, through wires 149 and 150 energize relay 148. This will operate armature 69 and 115, separating them from contacts 68 and 114 respectively. This interrupts the energizing circuits of both relay 34 and 111 and consequently both of these relays become de-energized. This lights the yellow light visible from both streets. This feature is introduced to provide for emergency control either at the intersection or from a distant point.

Connection VIII.—It will be noticed that when right of way is transferred from A Street to B Street, timing mechanism 80 times the warning interval during which the warning signal or yellow light is shown. As mentioned before, this timing mechanism is similar to the one shown in Fig. 4, and its resistance 19 was assumed adjusted so that it timed a period of 3 seconds. There is one slight difference in its construction from that of Fig. 3, and its complete wiring diagram is shown in Fig. 4. This difference consists in wires 151 and 152. Wire 152 is connected to one end of resistance 19 as shown, while wire 151 may be adjusted along resistance 19 by tap 153. If circuit between wires 151 and 152 is closed, this will shunt out a portion of resistance 19, and consequently the period timed by the mechanism will be less than 3 seconds, and may be, for example, 1 second. It will be noticed, furthermore, that if right of way is transferred from A Street to B Street, through the operation of timing mechanism 41, then the circuit

between wires 151 and 152 is closed because timing mechanism 41, in operating, causes armature 154 to touch contact 155. Thus the timing mechanism 80 will provide a short warning period, namely, 1 second. If the transfer is caused by the operation of timing mechanism 139, then circuit between wires 151 and 152 is not closed, and the warning signal provided by timing mechanism 80 will be 3 seconds in length because no portion of its charging resistance has been shunted out. When the transfer of right of way is from B Street to A Street, timing mechanism 40 performs in a manner similar to timing mechanism 80. In this case the shunting out of a portion of the resistance is accomplished through wires 156 and 157, armature 158 and contact 159.

The foregoing indicates that when right of way is transferred through the operation of either timing mechanism 41 or timing mechanism 121, the following warning period will be short, namely, 1 second. If the transfer is caused by the operation of either timing mechanism 137 or 139, the following warning period is long, namely, 3 seconds. This variable warning signal is in accord with traffic requirements. When traffic has ceased, on A Street for example, timing mechanism 41 transfers right of way to B Street, and since traffic has ceased on A Street, no longer warning signal need be given because there are no vehicles on A Street to be warned. The action is similar when timing mechanism 121 transfers right of way from B to A Street. If timing mechanism 139 transfers right of way from A Street to B Street, it means that continuous A Street traffic is being interrupted, and consequently a longer warning signal should be given so that the vehicles in A Street may have ample time to be brought to a stop. The action is similar when timing mechanism 137 transfers a right of way from B to A Street. It will be noticed that the mechanism provides a long or a short warning period in accord with the needs of the traffic.

Connection IX.—If all the switches are as shown in Figs. 5-6, except that switch 160 is closed, then as soon as right of way is given to B Street, armature 61 touches contact 161 and the energizing circuit E—E of timing mechanism 162 is made through wire 163, switch 160, wire 164, contact 161, armature 61 and wire 62. This timing mechanism is similar to the one shown in Fig. 3, and we shall assume that its resistance 19 is so adjusted that it times a period of 2 minutes. If right of way is taken away from B Street before the end of 2 minutes, the energizing circuit of timing mechanism 162 will be interrupted, its condenser will be discharged, and another 2 minutes of continuous B Street right of way must be shown before timing mechanism 162 will operate. Assuming there is no A Street traffic, then right of way would remain on B Street indefinitely, were it not for timing mechanism 162. After right of way has been showing for 2 minutes on B Street, timing mechanism 162 operates, causing armature 165 to touch contact 166. This through wire 163, contact 166, armature 165, wire 167 and wire 73 energizes relay 42. It will thus be noticed that the operation of timing mechanism 162 operates relay 42, thus performing the very same function that a vehicle approaching on A Street would have performed. If, when relay 42 operates, B Street traffic has ceased, right of way will be transferred to A Street. If B Street traffic has not ceased, then

right of way will eventually be transferred, as described above in the several cases, depending upon traffic conditions in B Street. We thus have a system which, in the event there is no traffic on one street, does, after a certain length of time, shift right of way to that street in order to allow pedestrians to cross. An additional important feature is that it does not arbitrarily transfer right of way at the end of the 2 minutes. It merely puts in a call on the street where the red light is being shown, and the system then takes care of that call just as though it had been caused by a vehicle approaching on A Street. The fundamental object of this system is to operate the signal lights in such a way that traffic is controlled most efficiently. Timing mechanism 162 does not disrupt that operation but merely insures that right of way will eventually be given to an opposing street even though there be no traffic upon it, in order to allow pedestrians to use the intersection.

If switch 168 is closed, timing mechanism 169 will be energized when right of way is given to A Street. This is accomplished through wire 81, armature 82, contact 170, wire 171, switch 168, energizing circuit E—E and wire 172. Timing mechanism 169 is similar to timing mechanism 162, and performs the same function for B Street that timing mechanism 162 performs for A Street. When timing mechanism 169 operates, it closes contact between armature 174, and contact 173, and thus through wire 172, contact 173, armature 174, wire 175, wires 48 and 47, operates relay 46. Right of way is now being called to B Street and will be transferred, as described above in the several cases. Briefly reviewing the operation, it will be noticed that when right of way has been showing continuously on one street for 2 minutes, right of way is called to the other street, and will be transferred to that street after not more than 30 seconds.

Connection X.—In all of the above description, it was noticed that timing mechanism 41 began to operate as soon as right of way appeared on A Street. Experience has shown that it is, in most instances, necessary to place the vehicle actuated devices quite some distance from the intersection. This occurs because vehicles should register their presence some time before they reach the actual intersection. This will allow the mechanism to either give them time to cross the intersection, or if right of way is to be taken away from the approaching vehicles, give them ample distance in which to stop. Suppose, for example, that the vehicle actuated devices are placed 150 feet from the intersection. Assume now that several vehicles approach on a street where the red light is showing, and assume also that they do not receive right of way immediately and are forced to stop. Eventually, of course, right of way will be transferred to that street and the vehicles will be given time to cross the intersection; in this case, 10 seconds. If all the vehicles got into motion at once, this time would be ample because the period provided should be sufficient to allow a moving vehicle, which has just actuated one of the vehicle actuated devices, to cross the intersection. However, the vehicles will not all move simultaneously. If, say, 10 vehicles are waiting, approximately 15 seconds will elapse before the last vehicle in the line gets into motion. Assuming there are no further operations of the vehicle actuated controls, the vehicle protection timing mechanism on that street will not be re-set and will, after 10 seconds, transfer right of way to the

opposing street. This obviously will occur some time before the last vehicle in the line has begun to move, and several of the vehicles will be stranded, without, however, leaving the system in such a condition that right of way will again be given to the stranded vehicles without requiring further actuation. It is thus necessary to provide an initial timing period long enough to allow all of the vehicles to get into motion, and furthermore, not to start the vehicle protection timer until the end of this initial period. If the system is operated in this manner, it will effectively take care of the time required to allow waiting vehicles to get into motion.

This initial timing period is provided by timing mechanism 176. The structure of the actual timing mechanism is similar to the one shown in Fig. 3. When power is supplied to the two wires E—E, current flows through wire 177, relay 178, and wire 179, operating relay 178. This causes armature 180 to touch contact 181, and condenser 182 would be charged through resistance 183. The amount of this resistance is variable by means of contact 184. Shunting condenser 182 is a glow tube 183 similar to the one previously described. When condenser 182 is charged to the critical voltage of tube 183, the tube becomes conducting and the energy stored in 182 discharges through tube 183 and relay 184, momentarily operating relay 184. This relay locks itself in through contact 185, armature 186 and wire 187. Contact 184 is mounted on a rack-arm 185, mounted so that it can slide longitudinally. This rack-arm is pulled against stop 186 by tension spring 187. When switch 188 is moved so that it touches contact 189, current flows from wire 190 through magnet 191, switch 188, contact 189, and wire 192, and magnet 191 will be continuously energized. Magnet 191 attracts armature 193, pivoted at 194. The armature 193 is hinged at 195, and when attracted by magnet 191, causes finger 196 to engage the teeth 197 of rack-arm 185. Thus if rack-arm 185 is moved to the left, the mechanism operated by magnet 191 will prevent its return motion. It will furthermore be noticed that moving rack-arm 185 to the left increases the resistance in the charging circuit of condenser 182. Assume that the rack-arm is moved so that timing mechanism 176 times a period of 10 seconds. In addition switch 106 must be open.

When right of way is being given to B Street, relay 34 is de-energized and current flows from wire 39, armature 38, contact 198, wire 199, relay 200 and wire 201, operating relay 200. Relay 200 operates armature 202 and locks itself in through contact 203, armature 202, wire 204, contact 205, armature 206 and wire 207. Assume that one or more cars are waiting on A Street, and right of way is about to be transferred from B Street to A Street. In the above description it will be remembered that timing mechanism 41 begins to operate as soon as right of way is transferred to A Street. With switch 106 open, however, the energizing circuit of timing mechanism 41 is interrupted and will not be closed until relay 208 operates, which will close the energizing circuit of timing mechanism 41, through wire 209, armature 210, contact 211, and wire 212. Relay 208 does not operate immediately as will appear from the following description. When right of way has been transferred to A Street, relay 34 will be energized, which allows current to flow from wire 39 through armature 38, contact 213, wire 214, wire 177, relay 178, wire 179, contact 215, armature 216 and wire 201, operating relay 178. This

establishes the charging circuit of condenser 182 through wire 39, armature 38, contact 213, wire 214, condenser 182, armature 180, contact 181, contact 184', resistance 183, contact 215, armature 216, and wire 201. Thus, the voltage of the supply is applied to condenser 182 through resistance 183, and the voltage of the condenser will begin to build up. As assumed before, 10 seconds will elapse before condenser 182 is charged up to the critical voltage of tube 183. Although right of way is being given to A Street, timing mechanism 41 has not begun to operate, and the vehicles waiting on A Street are given opportunity to get into motion and start across the intersection. They are in no danger of having timing mechanism 41 prematurely take away right of way. After 10 seconds have elapsed, condenser 182 reaches the critical voltage of tube 183 and the energy stored in condenser 182 discharges through tube 183 and relay 184, operating armature 186 which locks in relay 184 through contact 185, armature 186, wire 187, contact 215, armature 216, and wire 201. Relay 184 also operates armature 217, causing it to touch contact 218. This allows current to flow from wire 219, through contact 218, armature 217, wire 220, relay 208 and wire 207, operating relay 208. This closes contact between armature 210 and contact 211, completing the energizing circuit of timing mechanism 41.

It thus appears that the waiting vehicles have been given a period of 10 seconds in which to get into motion, and after this period, timing mechanism 41 provides the usual protection period,

which of course is resettable by additional vehicles approaching on A Street. The action from now on is just as described in the above cases. When relay 208 operates it causes armature 210 to touch contact 221, locking in relay 208 through contact 221, armature 210, wire 209, wire 105, contact 102, armature 101 and wire 104. At the same time relay 208 causes armature 206 to separate from contact 205, interrupting the locking circuit of relay 200 which becomes de-energized. When relay 200 becomes de-energized, armature 216 separates from contact 215, interrupting the energizing circuit of timing mechanism 176, and relay 178 becomes de-energized. This shunts adjustable resistance 222 through contact 223 and armature 180 across the terminals of condenser 182, and any energy stored there will be dissipated in resistance 222. If traffic approaches on B Street, then eventually right of way will be transferred to B Street. The moment A Street loses right of way, relay 34 becomes de-energized, establishing the energizing circuit of relay 200, which operates. The locking circuit of relay 200 is not completed until the end of the warning period. At the end of this period, timing mechanism 80 operates, separating armature 101 from contact 102 which interrupts the locking circuit of relay 208 which becomes de-energized, allowing armature 206 to touch contact 205. And the locking circuit of relay 200 is complete. The mechanism has now returned to the condition at the beginning of operations.

Timing mechanism 224 performs the same function for B Street that timing mechanism 176 performs for A Street. Similarly switch 124 must be opened. Switch 225 when moved to touch contact 226 causes magnet 227 to be continuously energized through wires 228 and 229. The armature 230, operated by magnet 227, is similar to the armature operated by magnet 191, and is arranged to engage the teeth 231 of rack-

arm 232. This rack-arm is pulled toward stop 233 by spring 234. When right of way is being given to A Street, relay 111 is de-energized, and through wire 235, wire 236, contact 237, armature 78 and wire 79, energizes relay 238. This relay locks itself in through contact 239, armature 240, wire 241, contact 242, armature 243 and wire 244. When right of way has been transferred to B Street, current flows from wire 79 through armature 78, contact 245, wire 246, relay 247, wire 248, contact 249, armature 250, and wire 235, operating relay 247. This establishes a circuit from wire 79, armature 78, contact 245, wire 246, condenser 251, armature 252, contact 253, contact 254, relay 255, contact 249, armature 250 and wire 235. Assume that rack-arm 232 is so adjusted that the amount of adjustable resistance 255 is of such a value that 10 seconds are required to charge condenser 251 up to the critical voltage of tube 256. After 10 seconds have elapsed, the energy stored in condenser 251 discharges through tube 256 and relay 257. Relay 257 locks itself in through contact 258, armature 259 and wire 260. At the same time a circuit is established through wire 261, contact 262, armature 263, and wire 264, through relay 265, and through wire 244. When relay 265 operates it locks itself in through contact 266, armature 267 and wire 268, at the same time through contact 269 and wire 270 completes the energizing circuit of timing mechanism 121. The operation of the device from this time on is similar to the operation of timing mechanism 176, except that the functions for A and B Streets are interchanged.

The above connection provides for an initial period during which vehicles may get into motion. While this may be satisfactory, in a great many installations, the device may occasionally be inefficient because the timing period, although adjustable manually, is fixed. Thus if, for example, 5 vehicles are waiting, the 10 second period may be just right. If more than 5 are waiting, a longer period may be desirable, and then again, if less are waiting, a shorter period would be ample. Thus it is desirable to provide an initial period that is proportional to the number of vehicles waiting. This may be accomplished on A Street, for example, by closing switch 271 and moving switch 188 so that it touches contact 272. When right of way is being given to B Street, and no vehicles are waiting on A Street, relay 200 will be energized, as described previously, and so will magnet 191, although the energizing circuit of magnet 191 is somewhat different, being made through wire 273, contact 215, armature 216, and wire 201. As will appear later, rack-arm 185' is resting against stop 186'. Every time a vehicle approaches on A Street, it momentarily operates relay 129, allowing current to flow from wire 274, contact 275, armature 276, wire 277, contact 278, armature 279, wire 280, switch 271, magnet 281, and wire 190, momentarily operating magnet 281. This attracts armature 282 which is similar to the armature operated by magnet 191. Finger 283 engages the teeth of rack-arm 185', notching the rack-arm forward by the distance of one tooth. Magnet 191 is so arranged that when the rack-arm is moved forward the distance of one tooth, finger 196 engages the teeth and prevents the return motion of rack-arm 185'. Thus, magnet 281 is momentarily energized every time a vehicle causes relay 129 to operate, and the rack-arm 185' is moved a distance proportional to the number of vehicles that have approached on A Street, while right of way 75

is being given to B Street. This provides that, since contact 184' moves with rack-arm 185', the amount of resistance 183 in series with condenser 182 is proportional to the number of vehicles waiting, and when timing mechanism 176 begins to time, the period timed by it will be proportional to the number of waiting vehicles. The operation of the device otherwise is the same. At the end of the period timed by mechanism 176, relay 184 operates and thus causes relay 208 to operate, all as described previously. At the same moment, relay 200 becomes de-energized and armature 216 separates from contact 215. This de-energizes timing mechanism 176; but, in addition, also de-energizes magnet 191, allowing finger 196 to move out of engagement with the teeth of rack-arm 185', and rack-arm 185' is pulled against stop 186' by spring 187'. Thus the mechanism has returned to its starting position, so that the next time vehicles register their presence on A Street while B Street is being given right of way, will again provide themselves with an initial period proportional to their number. It will furthermore be noticed that when right of way appears on A Street, armature 279 separates from contact 278, interrupting the notching circuit of magnet 281, and thus the initial period will not be increased by further vehicles registering on A Street.

30 An enlarged and more detailed diagrammatic view of the ratchet mechanism is shown in Fig. 7. In this enlarged view, in order to illustrate both energized and deenergized conditions of the electromagnetic devices, the ratchet actuating magnet 281 is assumed deenergized and its armature 282 is shown in deenergized non-actuated position with finger 283 disengaged from the rack teeth 197, and the ratchet holding magnet 191 is shown in its energized condition with finger 198 engaging the teeth 197. For this view it may be assumed that switch 271 of Fig. 5 is closed and switch 188 of Fig. 5 is in engagement with contact 272 for example and the rack 185' is shown in a partly advanced position away from stop 186' to illustrate its condition after several ratcheting actuations by traffic.

35 The operation of timing mechanism 224 which provides the initial period for B Street, can be adjusted similarly by closing switch 284 and moving switch 225 so that it touches contact 285. Thus, whenever a car operates one of the B Street ramps, relay 45 operates momentarily, allowing current to flow through wire 286, contact 287, armature 288, wire 289, contact 290, armature 291, wire 292, switch 284, magnet 293, and wire 228. Thus, magnet 293 is operated every time relay 45 operates. Magnet 293 operates armature 294 notching rack-arm 232 in a manner similar to the notching of rack-arm 185'. It will again be noticed that vehicles registering on B Street, after right of way has appeared on B Street, do not increase the initial period because the notching circuit is interrupted at contact 290 and armature 291, which are caused to separate when relay 45 operates.

40 While the above mechanism provides for an initial period that is proportional to the number of vehicles waiting, it may, under certain circumstances, be desirable to increase the initial period even after right of way has appeared on that particular street. The foregoing discussion shows that the initial period is proportional to the number of vehicles waiting, and presumably the last waiting vehicle has just started to move at the end of the initial period. But if further vehicles

have registered their presence, then sufficient time has not been allowed for them to get into motion. And thus it may be desirable to increase the initial period even during timing of the initial period. This may be accomplished for A Street 5 by closing switch 285, and as a consequence the notching circuit is not interrupted when right of way appears on A Street. If further vehicles approach on A Street, they will continue to operate magnet 281, moving rack-arm 185 so as to increase the charging resistance. Switch 286 is provided to perform the same function for B Street.

From the foregoing, it will be seen that a traffic control system is provided which operates in such 15 a way that:

1. The right of way is given successively to several traffic lanes in an order which may be predetermined, but in such a way that the length 20 of time one lane retains the right of way is dependent upon either the approach of vehicles in said lane or upon approach of vehicles in one or more other lanes, or upon both.

2. That a traffic lane which does not require the right of way cannot hold it to the disadvantage 25 of one which does.

3. That a vehicle whose progress is prevented by continuous stream of opposing traffic may not be required to wait more than a predetermined period of time, and that not later than the 30 end of said predetermined period of time said vehicle is given right of way for a period of time sufficient for it and following vehicles to cross the intersection.

4. That interfering lanes of traffic shall not be 35 given right of way simultaneously.

5. That a vehicle which has passed an actuating means is protected against opposing traffic for a period of time sufficient to permit said vehicle to pass the intersection of the traffic lanes.

6. That a vehicle which approaches an intersection on any lane of traffic is given immediate right of way on condition, and only on condition 40 that there be no opposing traffic in or immediately approaching the intersection.

7. That when a vehicle is not given immediate right of way or has right of way taken from it, before it has had sufficient time to cross the intersection, the system will be left in such a condition that right of way will return to the 50 delayed vehicle as soon as traffic conditions permit.

8. That periodically right of way shifts to another lane even though there be no vehicular traffic on that lane, in order to allow pedestrians 55 to cross the intersection.

9. That when the signal means and timing system is disconnected from the traffic actuated means, right of way may be given successively to the various traffic lanes according to a predetermined sequence and to each lane for a predetermined time interval.

10. That the signal means may be disconnected from the traffic actuated means and timing system and be operated manually.

11. That the timing system may be actuated to give a special signal for emergency use.

12. That the warning signal may be interposed between right of way and stop signals, the timing of said warning signal being in accord with the 70 traffic conditions existing at the moment.

13. That each vehicle is protected against opposing traffic for a period commensurate with its speed.

14. That if one or more vehicles, after passing 75

the actuating means, do not receive right of way immediately, they will be protected against opposing traffic when they do receive right of way, for a period of time sufficient to allow the last of the waiting vehicles to get started.

Summarizing certain of the salient features of the present invention, it will primarily be understood that an extremely efficient traffic control system is herein provided and by means of which among others, the several objects of the invention as specifically afore referred to are achieved. Contributing to the advantages of the applicants' embodiment of their invention are a number of factors which for the purpose of convenience may be identified (a) as variable amber, (b) periodic call, (c) variable increment, and (d) speed proportional control. It will be understood that, as indicated at the beginning of this specification, the present invention is primarily concerned with the "variable amber" and the "variable increment" among these several factors and not with the "periodic call" and "speed proportional control" factors, but that the latter two factors may in some circumstances be included in traffic control systems embodying either or both of the former two factors.

Dealing primarily with the question of variable amber, it will be understood that in the case of traffic approaching the intersection along one vehicle lane, and with no traffic in the second vehicle lane, there will be no necessity for a relatively delayed amber or transfer period. Accordingly, and by means of the present invention, the system will serve to transfer right of way to the vehicle lane over which traffic is approaching the intersection with a minimum delay period. On the other hand, where need for this delay period exists, as for instance, where there is a continuous stream of traffic along the vehicle lane which has the right of way and vehicles on the intersecting lane are awaiting the right of way, the transfer of right of way will only be completed after a maximum i. e. a three second delay period.

Dealing with the question of periodic call, it will be observed that in one form of the present embodiment, a functioning of the vehicle actuated control in effect occurs periodically even in the absence of vehicles. More particularly as set even if there is no traffic along one vehicle lane and continuing traffic along the other vehicle lane, the right of way over the latter will be interrupted at the end of a two minute and thirty second period for a minimum of ten seconds. This will allow pedestrians to cross. The reason for this will readily be understood in that the two minute timers in the event of continuing traffic along one lane have their functioning qualified by the thirty second timer. The former permitting the initiation of functioning of the latter after two minutes have elapsed. In the case of traffic over neither lane, the two minute timers would of course operate periodically to permit pedestrians to traverse the intersection without fear of traffic. It will, of course, be appreciated that this periodic call is entirely qualified in the case of continuous traffic approaching the intersection over both vehicle lanes.

With regard to the variable increment feature, it is understood that as previously brought out there is grave danger in the case of a number of vehicles awaiting right of way and all of which have operated the vehicle actuated control due to the necessary sluggishness of the last vehicles of this group. Consequently the right of way once accorded this group of vehicles would be liable

to be transferred before the last of the vehicles could negotiate the intersection. This difficulty, however, is anticipated by means of the present invention in that a timer functioning after right of way has been accorded such a vehicle group does not begin actually until a time period has elapsed proportionate to the number of vehicles which are awaiting the transfer of right of way. Accordingly, the last vehicle of this group will still be accorded a minimum right of way time period to negotiate the intersection. As a practical matter, it may of course be in many instances desirable according to the present invention to manually set this portion of the apparatus to approximate for this condition, but in any event, the time factor will be adequate and the system will take into account those vehicles arriving just after right of way has been accorded and which vehicles necessarily slow down as they become part of the group which is negotiating the intersection.

With respect to the speed proportional control, it will be understood that with this feature in the present embodiment, the timer resetting is not simply effected in an arbitrary manner which might in one instance result in undue delay to transfer of right of way and in another instance result in the transfer being effected at such an early moment as to trap a vehicle at the intersection, but that the resetting of this timer will actually be in proportion to the speed of the vehicle which is approaching the intersection.

Obviously, one or more of these factors might under certain instances be dispensed with and the several units of the apparatus while preferably embodying a construction substantially of the type illustrated and described, might be changed in numerous respects without departing from the spirit of the invention as defined by the claims.

Having described our invention, what we claim as new and desire to secure by Letters Patent is:

1. A traffic control system including, in combination, a signalling means adjacent the point of intersection of vehicle lanes to accord and interrupt right of way to traffic over said vehicle lanes, a timer controlling the operation of said signalling means, controllers adapted to be actuated by traffic in said lanes and connected to said timer to govern the functionings of the latter, said timer being potentialized during right of way signalling indication to vehicles traversing one lane to transfer such right of way to a second vehicle lane in which controller actuation has occurred and to accord a minimum period of right of way to the said second vehicle lane, and means acting in response to controller actuation in the second lane to extend such minimum period proportional to the number of vehicles awaiting such right of way and which have actuated said controller.

2. A traffic control system including, in combination, a signalling means adjacent the point of intersection of intersecting vehicle lanes to accord and interrupt right of way to traffic over said vehicle lanes, a timer controlling the operation of said signalling means, controllers adapted to be actuated by traffic in said lanes and connected to said timer to govern the functionings of the latter, said timer being potentialized during right of way signalling indication to vehicles traversing one lane to transfer such right of way to a second vehicle lane in which controller actuation has occurred and to accord a minimum period of right of way to said second vehicle lane.

- means acting in response to controller actuation to extend such minimum period proportional to the number of vehicles awaiting such right of way and which have actuated said controller, 5 and means forming a part of said system to further extend such minimum right of way period in the event of the operation of said vehicle actuated control by further vehicles traversing said latter vehicle lane, after right of way has been 10 accorded to the said latter lane.
3. A traffic control system including, in combination, a signalling means for according and interrupting right of way to traffic moving over intersecting lanes, a timer connected to and controlling the operation of said signalling means, 15 a traffic actuatable controller for one lane and connected to said timer to cause said signalling means to accord, responsive to controller actuation, right of way to such lane, means forming a part of said timer for maintaining the right of way accorded to either lane by said signalling means for at least minimum periods, and means functioning responsive to controller actuation and while right of way is interrupted with respect to the lane of the controller to automatically extend, when accorded, the minimum period 20 of right of way to such latter lane.
4. A traffic control system including, in combination, a signalling means for according and interrupting right of way to traffic moving over intersecting lanes, a timer connected to and controlling the operation of said signalling means, a traffic actuatable controller for one lane and connected to said timer to cause said signalling means to accord, responsive to controller actuation, right of way to such lane, means forming a part of said timer for maintaining the right of way accorded to such lane by said signalling means for at least a minimum period, further means forming a part of said timer whereby a period of right of way preliminary to said minimum right of way period may be accorded, the operation of such further timer means being dependent upon the functioning of the traffic actuatable controller a plurality of times prior to the transfer of right of way to the lane of said controller. 30
5. A traffic control system for a plurality of highways comprising stop and go signals therefor, means for energizing said signals to normally provide a cyclic display thereof in a predetermined periodic sequence, vehicle-responsive means for each of said highways, and means operated by said vehicle-responsive means to an extent dependent on the number of actuations thereof during that part of the periodic sequence when a stop signal is displayed on one highway to govern the energizing means to vary the period of display of the subsequent go signal for 40 said one highway.
6. A traffic control system for a plurality of highways comprising stop and go signals therefor, means for energizing said signals to normally provide a cyclic display thereof in a predetermined periodic sequence, vehicle-responsive means for each of said highways, and means operated by said vehicle-responsive means to an extent dependent on the number of actuations thereof during that part of the periodic sequence 45 when a stop signal is displayed on one highway to govern the energizing means to vary the period of display of the subsequent go signal for said one highway, the period of display of said subsequent go signal increasing as the number 50 of actuations increases.
7. A traffic control system for a plurality of highways comprising stop and go signals therefor, means for energizing said signals to normally provide a cyclic display thereof in a predetermined periodic sequence, vehicle-responsive means for each of said highways, and means operated by said vehicle-responsive means upon actuation thereof during that part of the periodic sequence when a stop signal is displayed to one highway and also during the signal period 55 preceding the display of the stop signal of said one highway to govern said energizing means to vary the period of display of the subsequent go signal for said highway in accordance with the number of actuations of said vehicle responsive means.
8. A traffic control system for a plurality of highways comprising stop and go signals therefor, means for energizing said signals to normally provide a cyclic display thereof in a predetermined periodic sequence, vehicle-responsive means for each of said highways, and means operated by said vehicle-responsive means during the period of a predetermined display of signals for said highways to govern said energizing means to vary the period of the next subsequent display of signals for said highways in accordance with the number of actuations of said vehicle-responsive means. 60
9. A traffic control system for a plurality of interfering traffic lanes comprising signalling means adapted to accord and interrupt right of way in such lanes, traffic responsive means in one of said lanes, a timer connected to the signalling means and traffic responsive means and operable in response to actuation of said traffic responsive means when the right of way is interrupted in said one lane to cause the signalling means to accord right of way to said one lane for a time period before right of way can again be interrupted, and means forming a part of said timer to vary said right of way time period in accordance with the number of actuations of said traffic responsive means occurring while right of way is interrupted prior to such accord of right 65 of way.
10. A traffic control system for a plurality of interfering traffic lanes comprising signalling means adapted to accord and interrupt right of way in such lanes, traffic responsive means in one of said lanes, a timer connected to the signalling means and traffic responsive means and operable in response to actuation of said traffic responsive means when the right of way is interrupted in said one lane to cause the signalling means to accord right of way to said one lane for a time period before right of way can again be interrupted, and means forming a part of said timer to vary said right of way time period in accordance with the number of actuations of said traffic responsive means occurring while right of way is interrupted prior to such accord of right of way, the right of way time period increasing as the number of such actuations increases. 70
11. A traffic control system for a plurality of interfering traffic lanes including in combination stop and go signals for the respective lanes, cyclic operating means for said signals adapted to display the same to signal "Go" successively to the several lanes and "Stop" to the lanes interfering with the lane having the go signal, traffic responsive means in at least one lane, timing mechanism to determine the time of display of the go signal to the respective lanes by said operating means, said timing mechanism includ- 75

- ing a time delay device having an adjustable time period for predetermining at least a part of the time of display of the go signal to said one lane, means connected with the cyclic operating means for connecting said traffic responsive means to said time delay device during the display of the stop signal to said one lane to adjust said device progressively for an increased time period responsive to a series of traffic actuations 5 and a holding device connected with said cyclic operating means to hold said time delay device so adjusted to time the next go signal display for said one lane and then reset said time delay device.
12. A traffic control system for a plurality of interfering traffic lanes including in combination stop and go signals for the respective lanes, cyclic operating means for such signals adapted to display the same to signal "Go" successively 10 to the several lanes and "Stop" to the lanes interfering with the lanes having the go signal, an electric timing device for predetermining at least a part of the time of go signal display to one lane by said cyclic operating means, circuit 15 means for operating said timing device including an impedance for determining the timing period of said device, step-by-step adjusting means for said impedance and having an initial position from which it is adapted to be operated to 20 increase said timing period by varying said impedance in steps, electromagnetic means for operating said step-by-step means one step at a time from the initial position to so increase said time period, traffic actuated means in said one 25 lane, means operated by said cyclic operating means to connect said traffic actuated means to said electromagnetic means to so operate the latter during display of a stop signal to said one lane for increase of said time period in successive steps by successive traffic actuations, and 30 locking means connected with said cyclic operating means and with said adjusting means for maintaining such time period adjustment as so increased into the next go signal display for 35 said one lane to determine the time of display of the latter and restore said adjusting means to said initial position.
13. A traffic control system for a plurality of interfering traffic lanes including in combination stop and go signals for the respective lanes, cyclic operating means for said signals adapted to display the same to signal "Go" successively to the several lanes and "Stop" to the lanes interfering with the lane having the "Go" signal, 40 an electric timing device for predetermining at least a part of the time of go signal display to one lane by said cyclic operating means, circuit means for operating said timing device including an impedance for determining the timing 45 period of said device, means including a ratchet for adjusting the amount of said impedance in said circuit means, the last named adjusting means having an initial position from which it is adapted to be advanced in steps to adjust 50 said impedance to increase said timing period, electromagnetic means for advancing said ratchet step-by-step from said initial position to so increase said time period, other electromagnetic means for holding when operated said 55 ratchet in any such advanced position, traffic actuated means in said one lane, means operated by said cyclic operating means to connect said traffic actuated means to operate the first mentioned electromagnetic means during display of the stop signal to said one lane for in- 60
- crease of the time period of said timing device in successive steps by successive traffic actuations, and further means operated by said cyclic operating means to operate said other electromagnetic means to hold said ratchet so advanced 5 until and during the next following go signal display for said one lane and then release it to restore it to its initial position.
14. A traffic control system for interfering traffic lanes including in combination signalling means, traffic actuated means in one lane, a timer connected to said signalling means and said traffic actuated means to cause said signalling means in response to operation of said traffic actuated means to accord right of way 10 to said one lane while interrupting right of way to the other lanes, means forming a part of said timer to maintain right of way so accorded for at least a minimum period of time before transfer of right of way from such lane can be effected, said means including a condenser, means for varying the charge on said condenser over a period of time and means operable upon said condenser reaching a predetermined charge to terminate said period and means operable by actuation of said traffic actuated means prior to according of right of way to said one lane to vary the rate of change of charge on said condenser during said right of way minimum period.
15. A traffic control system for the intersection of a plurality of interfering traffic lanes, comprising traffic signals for controlling traffic at the intersection, a source of power therefor, switch means in the circuit of said signals and said source for controlling the energization of said signals, mechanism including an electric timer for operating said switch means, an energizing circuit for said timer having a resistance for controlling the time cycle thereof, traffic responsive means for one of said lanes operably 20 connected to said mechanism, means associated with said mechanism and operated by actuation of said traffic responsive means for increasing said resistance to increase the time period of energization of one of said signals.
16. A traffic control system for the intersection of a plurality of interfering traffic lanes comprising traffic signals for controlling traffic at the intersection, a source of power therefor, switch means in the circuit of said signals and 25 said source for controlling the energization of said signals, mechanism including an electric timer for operating said switch means, an energizing circuit for said timer having a resistance for controlling the time cycle thereof, traffic responsive means for one of said lanes operably connected to said mechanism, means associated with said mechanism and governed by a plurality of actuations of said traffic responsive means for varying said resistance to vary said time cycle, each actuation varying the resistance from its immediately preceding value, the increment of the length of the time cycle increasing as the 30 number of actuations increases.
17. A traffic control system for the intersection of a plurality of interfering traffic lanes comprising traffic signals for controlling traffic at the intersection, a source of power therefor, switch means in the circuit of said signals and said source for controlling the energization of 35 said signals, mechanism including an electric timer for operating said switch means, an energizing circuit for said timer having a resistance for controlling the time cycle thereof, traffic responsive means for one of said lanes operably 40

connected to said mechanism, step-by-step adjusting means connected with said resistance and having an initial position and a plurality of additional positions to vary said resistance to 5 vary said time cycle progressively, an electromagnetic device for advancing said step-by-step means and operably connected to said traffic responsive means to advance said step-by-step means from its initial position through a plurality of positions to so vary said resistance progressively responsive to a plurality of actuations of said traffic responsive means, and an electromagnetic holding device for said step-by-step means operably connected with said mechanism 10 to hold said step-by-step means so advanced during a part of the time cycle and to reset said step-by-step means to its initial position in another part of the time cycle.

18. A traffic control system including in combination, signalling means to be disposed adjacent the point of intersection of traffic lanes, a timer for operating said signalling means to accord and interrupt right of way over said lanes, a traffic actuated control disposed in advance of 20 said intersection and connected to said timer to govern the operation thereof, timing means forming a part of said timer and acting in response to a functioning of said traffic actuated control to accord, through said signalling means, right 25 of way to one traffic lane for a minimum period of time, resetting means for said timing means and acting in response to a functioning of said traffic control during such right of way period to cause said timing means to supplement said 30 right of way period by a further time interval inversely proportionate to the speed of the traffic which actuated said control, and means functioning in the absence of right of way indication in one lane and in response to the functioning 35 of the traffic actuated control of such lane to delay initiation of operation of said timing means for a period proportionate to the number of actuations of said control which have occurred during such absence of right of way.

45 19. A traffic control system for interfering traffic lanes and including, in combination, signalling means, traffic-actuated controllers to be disposed in the lanes, a timer connected to said signalling means and controllers to cause said 50 signalling means to accord right of way to the lane in which controller actuation has occurred, while interrupting right of way to the other lane, means forming a part of said timer to cause such right of way indication to prevail for a minimum 55 period of time and means forming a part of said timer to accord through said signalling means a right of way period preliminary to said minimum period whereby to permit vehicles awaiting such right of way to get into motion after the 60 right of way is accorded to the lane in which controller actuation occurred.

20. A traffic control system for interfering traffic lanes including, in combination, signalling means and a control for operating said signalling means to accord and interrupt by the latter right of way over said lanes, traffic actuated devices in said lanes, said devices being connected to said control to cause a functioning of the latter, a unit forming a part of said control to extend to a vehicle operating the device of the lane to which right of way is accorded, a prolongation of said right of way to negotiate the intersection, and means functioning in response to an operation of the traffic actuated device 75 vice of one lane and in advance of the accorda-

tion of right of way to such lane to delay initiation of the unit's operation.

21. A traffic control system for interfering traffic lanes including, in combination, signalling means and a control for operating said signalling means to accord and interrupt by the latter right of way over said lanes, traffic actuated devices in said lanes, said devices being connected to said control to cause a functioning of the latter, a unit forming a part of said control 10 to extend to a vehicle operating the device of the lane to which right of way is accorded, a prolongation of said right of way to negotiate the intersection, means functioning in response to an operation of the traffic actuated device of one 15 lane and in advance of the accordation of right of way to such lane to delay initiation of the unit's operation, and manually controlled means for varying the time value of such delay.

22. A traffic control system for the intersection 20 of traffic lanes including in combination signalling means for according and interrupting right of way in said lanes, a timer connected to said signalling means to control the same, traffic actuated means in one of said lanes and connected to said timer, said timer including timing means responsive to operation of said traffic actuated means by traffic arriving at the intersection in one lane while right of way is interrupted therein to accord right of way thereafter 25 to said one lane for an initial predetermined minimum period to permit such traffic to start, further timing means for maintaining said right of way for a further minimum period immediately following said initial period to permit traffic 30 to enter or clear the intersection, and means operable by actuation of said traffic actuated means by further traffic arriving at the intersection during only said further minimum period to prolong accord of right of way beyond said further minimum.

23. A traffic control system for interfering traffic lanes including in combination signalling means for according and interrupting right of way in said lanes, a timer connected to said 45 signalling means to control the same, traffic actuated means in one of said lanes and connected to said timer, said timer including means responsive to operation of said traffic actuated means when right of way is interrupted in said one 50 lane to accord right of way to said one lane for at least a predetermined minimum period, two timing means for providing said minimum right of way period each timing means being adjustably presetable as to time interval, one timing 55 means being resettable to prolong the time required for it to complete its time interval and thus to prolong right of way beyond said minimum by operation of said traffic actuated means and the other timing means being non-resettable, 60 said non-resettable timing means timing one part of said minimum period and said resettable timing means being operable to time the other part of said minimum period upon completion of the time interval of the non-resettable timing 65 means.

24. A traffic control system including, in combination, a signalling means arranged adjacent the point of intersection of vehicle lanes to indicate right of way and caution to traffic traversing 70 said lanes, a timer controlling the operation of said signalling means and operating the latter to include a caution indication for a predetermined interval preliminary to transfer of right of way from one vehicle lane to the other, con- 75

5 trols adapted to be actuated by vehicles in said lanes for governing the functionings of said timer, means forming a part of said system to automatically diminish the interval of caution 5 indication preliminary to transfer of right of way by said signalling means to one vehicle lane and in the absence of controller actuation in the other vehicle lane, and means forming a part of said system and prolonging to a maximum 10 extent the interval of caution indication preliminary to transfer of right of way from one vehicle lane to another by said signalling means and in the case of actuation of the controllers of both lanes.

15 25. A traffic control system for interfering traffic lanes including signalling means, traffic-actuated devices in the lanes, a timer connected to said signalling means and said traffic actuated devices whereby in response to a functioning of 20 the device in one lane to transfer through said signalling means right of way to that lane, while interrupting right of way to the other lane, means whereby said signalling means in transferring right of way from one lane to the other 25 will provide a caution indication preliminary to such transfer and for a certain interval, and means forming a part of said timer to automatically diminish the interval of caution indication preliminary to transfer of right of way 30 by said signalling means and in the absence of operation of the traffic actuated device in the vehicle lane which is losing right of way.

35 26. A traffic control system for interfering traffic lanes including signalling means, traffic-actuated devices in the lanes, a timer connected to said signalling means and said traffic actuated devices whereby in response to a functioning of 40 the device in one lane to transfer through said signalling means right of way to that lane, while interrupting right of way to the other lane, means whereby said signalling means in transferring right of way from one lane to the other 45 will provide a caution indication preliminary to such transfer and for a certain interval, and means forming a part of said timer to automatically prolong to a maximum extent the interval of caution indication preliminary to transfer of right of way and in the presence of traffic in both of said vehicle lanes as indicated by actuations of said vehicle-actuated devices.

50 27. A traffic control system including, in combination, a signalling means to be arranged adjacent the intersection of a plurality of traffic lanes, means forming a part of said signalling means and providing cautionary, right of way, and interruption to right of way signal indications to traffic approaching the intersection over such lanes, a timer connected to and controlling the operation of said signalling means, a traffic 55 actuated controller for one lane and connected to said timer to cause said signalling means to accord, responsive to controller actuation, right of way to such lane, means forming a part of said timer for maintaining the right of way so accorded for a period of time, further means forming a part of said timer for transferring the right of way accorded by said signalling means away from such lane after the expiration of such period of time, and additional means forming 60 a part of said timer to cause a period of display of such cautionary indication by the signal

upon such transfer and dependent upon controller actuation during the period of display of the cautionary indication by said signalling means to vary such period.

28. A traffic control system including, in combination, a signalling means to be arranged adjacent the intersection of a plurality of traffic lanes, means forming a part of said signalling means and providing cautionary, right of way, and interruption to right of way signal indications to traffic approaching the intersection over such lanes, a timer connected to and controlling the operation of said signalling means, a traffic actuated controller for one lane and connected to said timer to cause said signalling means to accord, responsive to controller actuation, right of way to such lane, means forming a part of said timer for maintaining the right of way so accorded for at least a minimum period, further means forming a part of said timer and functioning responsive to controller actuation during such minimum period to extend the right of way indication of said signalling means beyond such period and by subsequent actuation to further extend such period, still further means forming a part of said timer for causing a transfer of right of way away from the lane of such controller upon the expiration of such extended period, and additional means forming a part of said timer for causing a period of display of said cautionary indication upon such transfer, such additional means being connected to said traffic actuated controller to cause the cautionary period to be varied by operation of said controller during such period.

35 29. A traffic control system for a traffic lane including signalling means for displaying right of way, denial of right of way and cautionary indications to such lane, traffic actuated means for such lane, signal controlling means to display right of way indication to such lane in response to operation of said traffic actuated means, means operating to interrupt such display and including timing means for providing a period of cautionary indication upon such interruption and means for varying such cautionary period responsive to actuation of said traffic actuated means during said cautionary period.

40 30. A traffic control system for a traffic lane including signalling means for displaying right of way, denial of right of way and cautionary indications to such lane, traffic actuated means for such lane, signal controlling means to display right of way indication to such lane in response to operation of said traffic actuated means, means operable to interrupt such display and including timing means for providing a period of cautionary indication upon such interruption, said timing means including a condenser, means for varying the charge on said condenser over a period of time, and means responsive to said condenser reaching a predetermined state of charge to terminate said period and means connected to said charge varying means for varying the rate of change of charge responsive to operation of said traffic actuated means during or immediately before the period of cautionary indication.
